DESIGN FOR A COMBINED POWDER PUFF AND LIPSTICK CONTAINER

Joan B. Lee, Richmond Hill, N. Y.

Application January 20, 1939, Serial No. 82,468

Term of patent 3½ years

To all whom it may concern:

Be it known that I, Joan B. Lee, a citizen of the United States of America, residing in Richmond Hill, county of Queens and State of New York, have invented a new, original, and ornamental Design for a Combined Powder Puff and Lipstick Container, of which the following is a specification, reference being had to the accompanying drawing, forming part thereof, wherein, puff and lipstick container showing my new design.

The rear view of the combined powder puff and lipstick container is substantially plain.

I claim:

The ornamental design for a combined powder puff and lipstick container, substantially as shown and described.

JOAN B. LEE.
